C. E. WISE,
PORTABLE TOOL FOR SECURING BINDING MATERIAL TO RECEPTACLES,
APPLICATION FILED JAN. 27, 1919.

1,376,597.

Patented May 3, 1921.

UNITED STATES PATENT OFFICE.

CLARENCE E. WISE, OF WASHINGTON, DISTRICT OF COLUMBIA.

PORTABLE TOOL FOR SECURING BINDING MATERIAL TO RECEPTACLES.

1,376,597.

Specification of Letters Patent.

Patented May 3, 1921.

Application filed January 27, 1919. Serial No. 273,409.

To all whom it may concern:

Be it known that I, CLARENCE E. WISE, a citizen of the United States, residing at Washington, District of Columbia, have invented certain new and useful Improvements in Portable Tools for Securing Binding Material to Receptacles, of which the following is a specification.

This invention relates to a portable hand tool for stretching, tensioning and twisting the free ends of wire lengths to assure the tight twisting of said ends of the wire for securely joining and locking the ends together, and is especially designed for the purpose of stretching, tensioning or tightening the wire which is frequently utilized in securing together the sections of a knock-down or collapsible crate, and is also used for binding or reinforcing wooden boxes and receptacles of various kinds used for shipping purposes by clamping the terminal ends of the wire and twisting the free ends until the said ends are tightly and securely joined.

The prime object of this invention is to provide a novel, simple, economical, strong, durable and thoroughly efficient tool for the purpose of stretching, tensioning, tightening and twisting the free ends of wire lengths, so that the said lengths will be firmly and properly tightened around a receptacle and the ends thereof will be caused to be safely and securely joined together by the twisting operation.

Another object of the invention is to so construct my novel device that when each free end of a wire length has been passed or secured around a receptacle to bind the same and shall have been passed between the jaws of the tool and the tensioning, tightening, and stretching jaws, the handle portions of said tool are pressed together and locked in their closed position, when the tensioning and stretching levers are forced rearwardly, which action carries their clamping jaws rearwardly, thereby tensioning, tightening and stretching the wire at its joining point, and at the same time causing the tool to assume a forward position in close proximity to the receptacle, at which time one or more turns of the tool is made which action will

twist the meeting ends of the wire together at the point of their juncture sufficiently to securely lock the tightening or stretching tension of the wire around said receptacle, when the tensioning and stretching levers are caused to assume their forward position, thus relieving further tension on the wire at and near the point of juncture, the tool then being given a sufficient number of turns to properly and securely join and lock the terminal ends of the wire by the twisting operation, after which the handles of the tool may be released and the twisted ends of the wire severed at any suitable point.

A further object of the invention is to provide simple and efficient means for effecting the clamping, tensioning, tightening or stretching, holding and releasing of the wire ends for the purposes such as set forth and described.

The foregoing and such other objects as may appear from the ensuing description are attained by the combination, arrangement, location, and novel features of construction of the parts hereinafter more fully described, illustrated in the accompanying drawings and particularly pointed out in the claims appended hereto, it being understood that slight changes in the form, proportions, and minor details of the construction may be resorted to without departing from the spirit or sacrificing any of the advantages of the invention.

In the accompanying drawings which form a part of the specification it will be seen that:

Figure 1 is a plan view of the novel device embodying my invention, showing the ends of the wire passed between the clamping jaws and jaws of the tensioning, tightening and stretching means, and showing a portion of a receptacle around which a binding wire has been passed.

Fig. 2, is a front elevation showing the tensioning, tightening and stretching levers broken away.

Fig. 3, is a side elevation of the device removed from the wire, showing the handles in locked position, and one of the tensioning, tightening and stretching levers in cross-section, and

Fig. 4, is a view in elevation showing a receptacle with the binding wire firmly and securely fastened around said receptacle and the ends of the wire joined, twisted and 5 locked together.

Similar characters of reference are employed to designate corresponding parts throughout the several views in the drawings.

10 In carrying out my invention it will be seen that it comprises two members 1 and 2, which are pivoted together by a suitable pin 3, the integral acting ends or fixed jaws 4, 4, each being provided near its outer end 15 portion with opposite diagonally arranged recesses 6 for the reception of one end of a wire length 7. Pivotally and removably secured cross-wise or transversely to the inner face of the lower fixed jaw 4, by a suitable pin 8, are two swinging bars or 20 levers 9, each having an upward extension 10, formed with an outer serrated or roughened clamping face 11, and pivotally mounted near the outer end of each of said bars 25 or levers 9, by a pin 12, is a wire tensioning, tightening and stretching lever 13, each of said levers being provided at its inner end with a serrated or roughened clamping face 14, and at the outer end portion of each of the swinging bars or levers 9 is formed an upward extension 15, constituting a stop for limiting the outward 30 movement of the levers 13. The upward extension 10 contacts with the upper rigid 35 jaw 4 when said bars or levers 9 are swung to their forward position, thus serving as a stop to limit their forward movement, while the depending extension 10' formed at the lower portion of each lever 9 contacts with the lower fixed jaw and 40 constitutes a stop to limit the rearward swinging movement of the levers.

Secured to the lower face near the outer end of each of said bars or levers 9, is a 45 pin 16, and to each of said pins is suitably secured one end of a coiled spring 17, adapted to serve the double purpose of securing the levers in both their foremost and rearmost positions when the spring is forced 50 beyond the pivotal center of said bars or levers by the manipulation of the levers 13.

Each of the two members 1 and 2 are provided with transverse grooves or recesses 18 adapted to engage with the rods 19, of a 55 link 20 which serves the purpose of locking and releasing the said members 1 and 2, when the said link is suitably manipulated for the desired purpose, and each of said members near their pivotal portion is provided with a recess 21, extending the entire 60 width of each member, and so arranged that when the members are separated a suitable distance apart the recesses will register, thus forming a continuous recess entirely across 65 both the upper and lower faces of both

members and constituting means for severing the wire when desired.

By reference to Fig. 3 it will be seen that the lower face of the upper fixed jaw 4 is provided with a recess, shown by dotted 70 lines, adapted to receive the head of the pin 8, when the members 1 and 2 are in the closed position shown.

While I have shown a form of link for locking the members 1 and 2 together for 75 the purpose herein referred to, it will be understood that any suitable or desirable means may be employed for the purpose stated.

The operation may be briefly described as 80 follows:

When the binding wire has been passed around a receptacle and caused to assume the position shown in Fig. 1, the free ends of the wire are passed within the recesses 85 formed in the fixed jaws and passed between the clamping faces of the bars or levers 9 and the levers 13, with the members 1 and 2 locked in closed position, the levers 13 then being forced rearwardly, thereby causing the bars or levers 9, and the levers 13 to assume the position shown in dotted lines in said Fig. 1, whereby the wire is properly tensioned, tightened and stretched at its point of juncture, and simultaneously causing the tool to assume a forward position in close proximity to the receptacle, as shown by dotted lines in Fig. 1, when one or more turns of the entire device is made, which action will twist the meeting ends of the 90 wire securely together at their point of juncture sufficiently to firmly lock the tensioning and tightening of the wire around the receptacle, then the bars or levers 9 and the levers 13 are forced forwardly and secured by the coiled spring in the position shown by full lines, Fig. 1, thereby relieving further tension on the wire at and near the point of juncture, the tool then being given a sufficient number of turns to properly and 95 securely join and lock the terminal ends in the twisted condition shown in Fig. 4, after which the handles or members 1 and 2 may be released and the twisted ends of the wire may be severed at any suitable point by the 100 severing means, such as set forth.

From the foregoing description, taken in connection with the accompanying drawings, it is believed that the construction and operation of my novel device will be fully and 110 clearly understood without resorting to a more extended and detailed explanation.

Having thus described my invention what I claim and desire to secure by Letters Patent is:—

1. A tool of the character described, comprising pivoted members, each member having a rigid jaw at one end thereof with diagonal recesses formed in each jaw, tensioning and tightening levers carried by one 130

of said jaws, and transversely mounted swinging levers pivotally secured to one of the jaws for the purpose set forth.

2. A tool of the character described, comprising pivoted members, each having a rigid jaw at one end with recesses formed in each jaw, tensioning and tightening levers supported by one of said jaws, and transversely arranged forwardly and rearwardly swinging levers pivotally mounted on one of the jaws.

3. A tool of the character described comprising pivoted members having a rigid jaw formed at one end, there being recesses formed in each jaw, transversely mounted levers pivot to one of the fixed jaws, and tensioning and tightening levers mounted on the first named levers.

4. A tool of the character described comprising pivoted members having a rigid jaw formed at one end, there being recesses formed in each jaw, transversely mounted swinging levers carried by one of the fixed jaws, each lever provided with stops to limit its forward and rear movement, and tensioning and tightening levers pivotally mounted on the first named levers.

5. A tool of the character described comprising pivoted members having a rigid jaw formed at one end, there being recesses formed in each jaw, forwardly and rearwardly swinging levers transversely mounted on one of said jaws, and forwardly and rearwardly swinging tensioning and tightening levers carried by the first named levers.

6. A tool of the character described comprising pivoted members, each having a rigid jaw formed at one end, there being recesses formed in each jaw, transversely arranged swinging levers pivotally mounted on one of the fixed jaws, each lever formed with an upwardly extended clamping jaw, and a tightening and tensioning lever carried by the first named lever.

7. A tool of the character described comprising pivoted members, each having a rigid jaw formed at one end, there being recesses formed in each jaw, levers transversely mounted and pivotally secured to one of the fixed jaws, each lever having an upper and a lower extended stop portion, and formed with an upwardly extended roughened clamping jaw, and a tensioning and tightening lever pivotally mounted on each of the first named levers.

8. A tool of the character described comprising pivoted members, each having a rigid jaw at one end, there being recesses formed in each jaw, forwardly and rearwardly swinging levers pivotally mounted on one of the jaws, each of said levers having an upwardly extended roughened clamping surface, and a swinging, tensioning and tightening lever provided with a clamping

inner end and pivotally mounted on each of the first named levers.

9. A tool of the character described comprising pivoted members, each having a rigid jaw at each end, there being recesses 70 formed in each jaw, transversely mounted swinging levers pivotally secured to one of the jaws, a coiled spring secured to each of said levers adapted to secure said levers in their adjusted position, and a tensioning and 75 tightening lever pivotally mounted on each of the first named levers.

10. A tool of the character described comprising pivoted members, each having a rigid jaw at each end, there being recesses 80 formed in each jaw, forwardly and rearwardly swinging levers pivotally secured to one of the fixed jaws, a coiled spring secured to each of said levers adapted to retain the levers in both their foremost and 85 rearmost positions, and a tensioning and tightening lever carried by each of the first named levers.

11. A tool of the character described comprising pivoted members, each having a 90 rigid jaw at each end, there being recesses formed in each jaw, forwardly and rearwardly swinging levers pivotally secured to one of the fixed jaws, each lever provided with an upward and a downward extended 95 stop portion, and a roughened clamping surface, a coiled spring connected to each of said levers, and a tensioning and tightening lever pivotally mounted near the outer end of each of the first named levers.

12. A tool of the character described comprising pivoted members, each having a rigid jaw at one end, there being recesses formed in each jaw, transversely arranged levers pivotally secured to one of the fixed jaws, each lever formed with stops to contact with the rigid jaws, a roughened clamping face and an upwardly extended stop at each end thereof, and a tensioning and tightening lever pivotally mounted on each of 110 the first named levers, and provided at its inner end with a roughened clamping face.

13. A tool of the character described comprising pivoted members, each having a rigid jaw at one end, there being recesses 115 formed in each jaw, forwardly and rearwardly swinging levers transversely arranged with respect to the rigid jaws and pivotally mounted on one of said jaws, a coiled spring connected at each end to each 120 of said levers, a forwardly and rearwardly swinging, tensioning and tightening lever pivotally mounted on each of the first named levers, and an upwardly projecting stop formed at the outer end of each of said first 125 named levers for limiting the outward movement of the tensioning lever.

14. A tool of the character described comprising pivoted members, each having a rigid jaw at one end, there being recesses 130

formed in each jaw, transversely arranged swinging levers pivotally secured to one of the fixed jaws, each lever having an upward and downward extension adapted to contact 5 with the rigid jaws, a roughened clamping surface, and an upward projecting stop formed at the outer end, a coiled spring con-

nected at each end to the outer end portion of each lever, and a tensioning and tightening lever pivotally mounted on each of the 10 first named levers, and provided with a roughened clamping surface at its inner end.

CLARENCE E. WISE.
